UNITED STATES PATENT OFFICE

2,646,184

LABEL MACHINE

Clarence Ouellette, Springfield, Mass., assignor to
 Wrap-King Corporation, West Springfield,
 Mass., a corporation of Massachusetts

Application November 30, 1951, Serial No. 259,255

1 Claim. (Cl. 216—55)

1

This invention relates to improvements in labeling apparatus and this application is a continuation in part of an application filed by me on October 31, 1950, as Ser. No. 193,222, now Patent Number 2,613,008, issued October 7, 1952.

The principal objects of the invention are the provision of means in association with the heating surface of a heater to prevent contact of labels with said surface as they are moved therepast by a label carrying drum.

According to the prior art apparatus, labels having a thermoplastic surface have been passed over a heated member in direct contact therewith to soften the thermoplastic for subsequent application of the labels to objects or packages.

This is very objectionable for the reason that the thermoplastic adheres to the surface of the heated member. This requires frequent cleaning of the heating surface which results in shutdown time of the apparatus.

According to the novel features of this invention, means is provided for holding the label outwardly of the heater surface whereby the thermoplastic is adequately softened while the heater surface is not smeared with the adhesive. Said means includes relatively spaced blades out of contact with the heater or its surface and these may be made from material having greater heat dissipating characteristics than the heater itself to obviate adhesive adhering to the blades.

All of the above objects I accomplish by means of such structure and relative arrangements of parts thereof, as will fully appear by a perusal of the description below and by various specific features which will be hereinafter set forth.

To the above cited and other ends and with the foregoing and various other novel features and advantages and other objects of my invention as will become more readily apparent as the description proceeds, my invention consists in certain novel features of construction and in the combination and arrangement of parts as will be hereinafter more particularly pointed out in the claim hereunto annexed and more fully described and referred to in connection with the accompanying drawings wherein:

Fig. 1 is a front elevational view of a portion of label applying apparatus having the novel features of the invention associated therewith; and

Fig. 2 is an enlarged sectional plan view on the line 2—2 of Fig. 1.

Referring now to the drawings more in detail, the invention will be fully described.

So much of label apparatus of the before-mentioned application is shown as will facilitate an understanding of the present invention.

2

A housing is represented by 2 having a drum shaft 4 rotatable therein and extending forwardly therefrom. A bracket 6 is secured to the housing and extends forwardly therefrom with the outer end of shaft 4 rotatable therein.

A drum 10 is rotated by shaft 4 in the direction of the arrow shown and has a jaw 12 cooperating with a member 14 to engage and grip the forward end of a label and carry it in the direction of the arrow past a heater indicated by H.

Guides 18 are shown for supporting a vertical stack of labels L, and a lever 20 oscillatable by a shaft 22 journaled in the housing has a suction cup 24 for engaging the lowermost label of the stack.

As the said lowermost label is engaged by the suction cup, the lever 20 swings clockwise to present the forward edge of the label to the members 12 and 14 of the drum.

Said members 12 and 14 grip the label and as the drum rotates said label is carried past the heater H as in the application referred to.

The heater H is secured to the forward side of the housing 2 and encloses heating means which may be a resistance coil connected in an electric circuit. The arrangement is such that an inner curved surface 26 of the heater is heated so as to soften the thermoplastic on the labels as they are carried therepast by the drum 10.

30 The curved surface 26 of the heater is provided with transversely spaced grooves 28, the bottoms of which are arranged as is the surface 26 complementary to the outer curved label supporting surface 30 of the drum.

35 Curved blades 32 have upper ends such as 34 which are secured by screws 36 to a member 38 that is secured to bracket 6 by a screw or screws such as 40. These blades may be secured in other ways.

40 The blades are curved so as to be complementary to the curvature of the label drum and have inner surfaces 44 spaced outwardly or away from the curved surface 26 of the heater.

The sides of the blades are spaced from the 45 sides of the grooves and the rear or inner edges thereof are spaced from the bottoms 18 of the grooves so as to provide air spaces between the blades and heater.

The blades not being in contact with the heater, the heat of the heater is not transmitted directly to the blades so that the temperature of the blades may be somewhat less than that of the heater which is desirable.

To provide a lower temperature of the blades 55 than that of the heater, the blades may be formed

from metal which is adapted to dissipate heat more rapidly than the metal at the curved surface of the heater. As an example, the bars may be formed from aluminum and the curved surface of the heater may be formed from cast iron or the like.

It will be desired that the heater be such as to provide the desired temperature for softening the adhesive while the bars are not intended for this function. To that end, the selection of metals in combination with the relationship of the bars and heater will accomplish the result.

As the label drum rotates to carry a label, having thermoplastic or some heat responsive adhesive or coating on the face thereof, past the curved surface of the heater, the coated surface of the label is held out of contact with said curved surface. The objection of the adhesive adhering thereto which would interfere with the passage of labels therepast and frequent cleaning thereof is obviated.

The blades may be relatively thin transversely and the spaces between the blades and walls of the grooves may be varied in order to accomplish the desired results. In any case, the blades will perform their function without in any way interfering with the action of the heating surface of the heater on the coating of the labels but will insure that the heating surface is kept clean so that shut-down for cleaning is avoided.

Heretofore not only has the heating surface of the heater been smeared with adhesive so that the surface requires cleaning, but the adhesive offers resistance to the passage of labels thereover. Furthermore, labels have been devoid of the adhesive adhering to the heating surface.

By means of the bars which do not remove any appreciable amount of adhesive from the labels if any at all, the labels slide readily along the bars and the cleaning of the heating surface does not occur.

The invention may be embodied in other specific forms without departing from the essential characteristics thereof. Hence, the present embodiments are therefore to be considered in all respects merely as being illustrative and not as being restrictive, the scope of the invention being indicated by the appended claim rather than by the foregoing description, and all modifications

and variations as fall within the meaning and purview and range of equivalency of the appended claim are therefore intended to be embraced therein.

What it is desired to claim and secure by Letters Patent of the United States is:

Mechanism for heating softenable adhesive on labels comprising, a support, a drum rotatable relative to said support on a horizontal longitudinal axis having a label supporting cylindrical face concentrically related to said axis for carrying a label having heat softenable adhesive on an outermost side thereof, a heater secured to said support having an inner cylindrical heating surface arranged concentrically relative to said axis and so disposed relative to the face of said drum as to be spaced outwardly away from the outermost face of a label on said face, the heating surface of the heater provided with grooves there-around of a certain transverse width and spaced longitudinally of the axis of rotation of the drum and extending into the heater and having relatively spaced sides and bottoms, and blades in the form of elongated arcuate strips of relatively greater width than thickness disposed in said grooves having an end thereof secured to said support, the thickness of said blades being relatively less than the width of said grooves whereby outer sides thereof are out of contact with the sides of said grooves, outer edges of said blades being spaced away from the bottoms of said grooves with opposite inner edges thereof disposed beyond the inner surface of the heater toward the axis of the drum and adapted to be engaged by the outermost sides of labels on said drum to space said sides away from the heating surface.

CLARENCE OUELLETTE.
